FREDERICK HUMBERT FAIRWEATHER, OF BRIDGEPORT, CONNECTICUT.

AIR GUN.

1,404,689.

Specification of Letters Patent. Patented Jan. 24, 1922.

Application filed November 15, 1919. Serial No. 338,398.

To all whom it may concern:

Be it known that I, FREDERICK HUMBERT FAIRWEATHER, a citizen of Canada, residing at Bridgeport, in the county of Fairfield and State of Connecticut, have invented certain new and useful Improvements in Air Guns, 5 of which the following is a specification.

My invention relates to improvements in air guns, and the object of my improvement 10 is to provide an efficient manner of compressing the air and retaining the compressed air, to provide a magazine that is operative with projectiles in the form of bullets of spherical form and means for retaining the bullet in the firing position with the muzzle depressed, to provide a breech mechanism that permits of the use of different types of projectiles, having convenient means for loading, and a stock structure 15 of a form that is cheap and convenient to manufacture.

In the accompanying drawing:—

Figure 1 is a longitudinal sectional elevation along a vertical central plane, with the parts in the loaded position, ready to discharge.

Figure 2 is a transverse sectional view on the line 2—2 of Fig. 1.

Figure 3 is a transverse sectional view on the line 3—3 of Fig. 1.

Figure 4 is an enlarged view of certain parts shown in Fig. 1, showing the magazine mechanism and showing the breech in the open position.

Figure 5 is a plan view of the breech, showing the locking device.

Figure 6 is a fragmentary sectional view, corresponding to Fig. 1, showing a modification of air retaining valve structure.

Figure 7 is a diagrammatic view of the parts that form the toggle structure for locking the plunger for holding the air under compression.

My improved air gun comprises a stock 10 45 that supports the different parts, consisting of the barrel 11, air compressing mechanism 12, valve mechanism 13, and a magazine 14, the barrel 11 being so mounted as to have longitudinal sliding movement and a rotative movement relatively to the stock for providing access to the interior of the breech

15 for the purpose of loading with darts and other special projectiles, other than spherical bullets.

The magazine 14 is at the front end portion of the stock 10 and the barrel 11 is operatively mounted by its rear end portion on the upper side of the said magazine.

The butt 16 is at the rear end of the stock 10 and has on the under side a recess 17 60 that is of suitable form for housing the air compressing mechanism 12.

Intermediate the butt 16 and the magazine 14 is the shank portion 18 of the stock 10, which is crossed generally vertically by 65 a chamber 19 in which is housed the valve mechanism 13. The said vertical valve chamber 19 is extended outwardly for connecting with the rear end portion of the bullet chamber 20 and housing the front 70 end portion of the collapsible rubber tube 21 and a passage 22 serves to house the rear portion of the said tube 21.

The rubber tube 21 connects the front end of the air compressor cylinder 23 with 75 the said rear end portion of the bullet chamber 20, passing through the valve chamber 19, where it is engaged by suitable valve devices 13.

The said valve devices or valve mechanism 80 13 correspond generally to the form shown and described in the patent issued to me July 8, 1919, No. 1,309,321, comprising a backing plate 24 on the upper side that closes the upper side of the chamber 19, 85 against which the tube 21 is forced by the reciprocating plunger 25, positioned on the lower side of the said tube 21.

The plunger 25 is capped on the upper end, that engages with the tube 21, by a rubber cushion head 26 and has a notch 27 in the side for receiving the upper end of the pivoted trigger lever 28 for being locked in the upper position for holding the tube 21 compressed, the said trigger lever being operatively engaged by a spring plunger 29 that serves to position the same for cooperation with the valve plunger 25.

In the form shown in Fig. 1 the effectiveness of the valve mechanism 13 is improved 100 by means of an inwardly projecting rib 30 that is opposed to the cushion head 26,

whereby the tube 21, when the valve parts are engaged, assumes the form of a reverse curve. As shown in Fig. 1 the rib 30 is formed by means of an inward bend or indentation of the backing plate 24.

In the modified form of trigger and valve mechanism shown in Fig. 6 the rib 30^a is in the form of an outward bend of the backing plate 24^a, so as to form a concave seat on the inner side and the cushion head or pad 26^a that cooperates therewith has a rounded upper end.

The cushion head 26^a is rigidly mounted on the upper end of a swinging member 31 that is pivotally connected by its lower end with the upper end of the trigger lever 25^a that is mounted on the pin 32, the lower end of the said trigger lever 25^a being exposed and accessible for operation as the trigger.

20 The swinging member 31 serves as the valve device for collapsing the valve tube 21, the cushion head 26^a, that is made of rubber, serving as the contact portion that contacts with the said tube 21 and being adapted to 25 yield slightly so as to permit the parts to be shifted between the locked or valve-closing position and the open position.

30 The interior wall structure of the chamber 19^a, in which the swinging member 31 and the body portion of the trigger lever 25^a to which it is connected are operatively housed, is of suitable form for limiting the movement of these parts to the extreme positions, comprising as one extreme the locked 35 and valve closing position shown in full lines in Fig. 6, and the open position as the other extreme, and indicated by broken lines in the said Fig. 6.

40 As described, the swinging member 31 and the trigger lever 25^a cooperate as a toggle device, so that an increased power effect is obtained in the reverse movement of the trigger lever in the final stages of collapsing the tube 21 that compensates for the relatively 45 increased resistance usually involved in operating on the said tube 21 during such final stages.

50 The air compressing mechanism 12 comprises the cylinder 23 that is open at the rear end and terminates at the front end in the form of the nipple 33 that receives the rear end of the rubber tube 21.

55 The piston 34 that operates in the cylinder 23 is provided on the front end with packing 35 of cupped form, of leather or celluloid, after the manner of packing hydraulic pistons, and at the rear end is connected with the link 36 by means of the pivotal pin 37.

60 The link 36 extends rearwardly from the piston 34 and has its rear end pivotally connected by means of the pin 38 with the front end of the rear branch or arm 39 of the bell crank lever 40 that is pivotally connected to the stock 10 at its rear end by means of the

pin 41. The front portion of the bell crank 65 lever 40 is bent and shaped suitably to serve as the operating handle 42, which in one position, corresponding to the position of compression of the air in the cylinder, engages with the opposed portion of the stock 10, so 70 as to serve as a stop for limiting the movement of the parts and locking the said parts, in cooperation with the resilient or spring effect of the compressed air in the cylinder, being the position shown in Fig. 1. The link 75 36 and the arm 39 cooperate as toggle members, being brought to a position back of the line of centers when locked in the manner described, and as indicated in Fig. 7.

The parts are shown in the open position 80 by the broken lines in Fig. 1.

The line of centers is indicated by the dash line in Fig. 7.

The advantage of the toggle effect in the 85 operation of the bell crank compressing lever 40 corresponds to that of the toggle in the trigger and valve device described and shown in Fig. 6, in that there is increased power effect in the final stages to compensate for the increased resistance due to the high 90 pressure of the confined air.

95 The breech structure 15 is in the form of a tube or sleeve that is seated in a depression 43 in the stock 10 and in the bore thereof are entered the front end of the tube 80 that 100 contains the bullet chamber 20 and the rear end of the barrel 11, the said tube 80 being fixedly secured within the rear end portion of the said bore, and the barrel 11 being slidably housed in the front portion 100 thereof. The rear part of said front portion of the bore is designated by the character 47, and serves as the projectile receiving chamber.

105 Adjacent the front end of the bullet chamber 20 the side wall of the breech tube 15 is provided with openings on opposite sides, comprising the opening 44 on the upper side that is of appreciable size, suitably for admitting darts to the portion 47 of the bore 110 of the breech tube 15, and on the under side the perforation 45 that is adapted to admit bullets 46, generally of spherical form, when the barrel 11 is positioned in the forward position so as to provide access to the bore 115 space or projectile receiving chamber 47.

115 In front of the projectile receiving chamber 47 the side wall of the breech tube 15 is provided with a guide slot 48 for a cam device and handle structure to be described. 120

125 The bullet chamber 20 is of tubular form, has the rear end 49 flared for receiving the end of the rubber tube 21 and a metal retaining sleeve 50, has an inwardly projecting pin 51 that serves as a rear stop for the bullet 46, has the front end beveled to form a tapered seat 52 for the opposed end of the barrel 11, and has an opening 53 in the

upper wall of the part that is telescoped within the breech sleeve 15 for housing a ball 54 or other device that is part of a spring plunger device. The said sleeve 15 has an opening 55 in registration with the opening 53 that completes the chamber for the said spring plunger device. The said chamber, composed of the opening 53 in the side wall of the bullet chamber 20 at the inner end and the opening 55 in the side wall of the breech sleeve 15 at the outer end, is closed at the outer end by the opposed part of the retaining band 56, that serves to hold together the parts of the gun structure, as will be described, and is positioned suitably to cover the opening 55.

The ball 54 is backed by the coil spring 57, and the mouth of the opening 53 is partially closed, so as to normally permit the ball 54 to project into the bore 58 sufficiently to serve as a stop for preventing the bullet 46 from rolling out of the bullet chamber when the muzzle is depressed. The spring 57 is relatively light, so as to be adapted to yield during discharge, when the bullet contacts with the ball 54 and momentarily forces the said ball 54 away from its seat in passing by the opening 53.

The barrel 11 is a sliding fit in the bore 47 and has a longitudinal movement therein sufficient in extent to permit the inner tapered end 59 to be seated against the end 52 of the bullet chamber 20 at the innermost position and at the outermost position to uncover the breech opening 44 and the bullet opening 45.

For manipulating the barrel 11, and also for guiding and locking the same, there is provided, as shown, a ball handle 60 that is mounted on a stem 61, the latter traveling in the slot 48 in the breech sleeve 15. The slot 48 is longitudinally directed for the most part and has at the rear end a helical branch 62 that serves as a cam slot for cooperating with the stem 61 for locking the barrel 11 in the rearmost position, corresponding to the position for firing.

The retaining band 56 is positioned adjacent the front end of the shank 18, extends around the stock 10 and the rear end portion of the breech sleeve 15, the two end portions 63 being brought together at the upper side and held together by rivets 64. The said two end portions 63 are positioned in face to face contact, so as to project upwardly above the breech sleeve 15, and the extreme or tip ends are tapered so as to combine to form a V-shaped depression that serves as the rear sight.

The front portion of the barrel 11 is operatively held in place by retaining band 66 that is generally similar to the band 56 and also serves as a sight, there being differences in detail in that the barrel 11 is slidably

mounted within the said band 66 and the ends 67 are shaped so as to combine to form an A-shaped projection 68 that serves as the front sight.

The magazine 14 comprises a storage chamber 69 for the storage of a supply of bullets 46 that is closed at the front end by a screw plug 70 and a feed wheel chamber 71 intermediate the said storage chamber 69 and the perforation 45 in the breech sleeve 15 that serves as a channel for the bullets. The feed wheel chamber 71 is an operative fit for the wheel 72 that is housed therein, being mounted on the shaft 73, and has an opening 74 that communicates with the storage chamber 69, for exposing the bullet receiving notches 75 in the wheel 72. As shown, there are four such notches 75, equally spaced around the periphery of the wheel, and they are adapted to individually receive a bullet and deliver the same to the passage 45 when the wheel is turned. From the passage 45 the bullet is delivered to the bullet chamber 20 by gravity when the gun is held vertically and the barrel 11 is pushed outwardly so as to uncover the said passage 45.

The shaft 73 projects through the side of the stock 10 and is provided on the outer end with a wheel handle 76 that has notches 77 that correspond in number and position to the bullet receiving notches 75 of the feed wheel 72, suitably to serve as indicating means for indicating the angular movement and position.

The stock 10, as will be noted, is provided with a plurality of chambers and channels of peculiar form, and I find it desirable in order to facilitate providing these different features to make the stock 10 of two mating parts that meet along the medial plane, the parts being similar, except that one is right handed and the other left handed.

Thus in Fig. 1 there is shown in side elevation substantially the entire left hand stock member 78. From an inspection of the said Fig. 1 and also Figs. 2 and 3 it will be noted that the stock 10 is made of wood.

The bands 56 and 66 that serve to hold the several parts to the stock 10 in the manner described, also serve to hold the two stock members 78 together, suitably to serve as a unitary structure.

I claim as my invention:

1. In an air gun having an air compressing chamber and a plunger operative therein, a packing for the said plunger of cup form for engaging with the side walls of the said chamber, and the said packing being formed of celluloid.

2. In an air gun, a pump for compressing air having a cylinder, a piston operative in the said cylinder, and a toggle device for operating the said piston, the said toggle de-

- vice comprising two pivotally connected members, one end of one of the said members being connected to a fixed support, the said cylinder being open at one end, and the other 5 of the said members being projected into the said cylinder and mounted by its end on the said piston.
3. In an air gun as described in claim 2, the other of the said toggle members being 10 provided with an extension that serves as a handle for operating the said pump.
4. In an air gun, a stock, a pump cylinder housed in the said stock, the said pump cylinder having the front end connected to the 15 gun barrel and having an open rear end, a piston housed in the said cylinder, a lever actuating device having a handle at one end and having the other end pivotally connected to the said stock, and a link projected 20 through the said open rear end of the cylinder, connected by one end to the said device, and connected by the other end directly to the said piston.
5. In an air gun, a collapsible tube for 25 connecting the air chamber with the barrel and a valve device for compressing the said tube, a stock having a chamber for the said tube and a cross-chamber for housing the said valve device, the said valve device comprising a trigger member in the form of a 30 lever, pivotally connected to the said stock, having one end extended beyond the stock for use as a trigger, and having the other end extended into the said cross-chamber, 35 and a swinging member for engaging with the said tube pivotally connected to the said other end of the trigger member.
6. In an air gun as described in claim 5, a backing device in the form of a plate engaged 40 with side of the tube opposite to the said valve device and adapted to serve as a seat for the tube, and the said devices being one of concave form and the other of convex form for the portions that engage with the tube.
- 45 7. In an air gun, a breech structure having a bullet chamber, the side wall of the said bullet chamber being provided with a lateral chamber that connects with the said bullet chamber by means of a reduced opening, a plunger housed in the said lateral chamber and adapted to project through the 50 said reduced opening, and a backing spring in the said lateral chamber that tends to 55 position the said plunger in the said lateral chamber.
- 60 8. In an air gun, a breech sleeve in the form of a tubular structure, having an opening in the side wall for admitting a projectile, a bullet chamber member telescoped 65 within the rear portion of the bore of the said structure, fixedly secured therein, and having a bore that serves as a bullet receiving chamber for receiving a projectile ad-
- mitted through the said opening, and a barrel telescoped by its rear end in the front portion of the said bore, and the parts being constructed and arranged so that the said barrel has limited rotative and longitudinal movement relatively to the said breech sleeve 70 for permitting of covering and uncovering the said opening and locking the said barrel in position.
9. In an air gun as described in claim 8, the end wall of the said bullet chamber member that is opposed to the said opening in the breech sleeve being of tapered form to facilitate the passage of projectiles from the breech sleeve to the bullet receiving chamber.
- 75 10. In an air gun as described in claim 8, guide and locking means for the said barrel comprising a handle device that projects radially from the said barrel, the said breech sleeve having a main slot extending longitudinally for the passage of the said handle device and a locking branch of helical form at one end of the said main slot, one border wall of the said locking branch serving as a cam device in cooperation with the said 80 handle device for locking the barrel in position.
11. In an air gun as described in claim 8, the said breech sleeve having a second opening for admitting projectiles, one of the said 85 openings being adapted to admit bullets and the other being adapted to admit darts.
12. In an air gun, a stock structure, a barrel supported by the said stock structure, the said stock structure being provided with 90 a bullet receiving chamber at the rear end of the said barrel, having bullet storage chamber at one side of the said barrel, and having a feed wheel chamber intermediate the said storage chamber and receiving 95 chamber and connected with the said chambers by passageways, and a feed wheel rotatively housed in the said feed wheel chamber and having notches for receiving bullets from the passage connecting with the storage chamber and delivering the said bullets to the passage connecting with the said bullet receiving chamber.
- 100 13. In an air gun as described in claim 12, the said feed wheel having a disk handle, 105 and the said handle having notches in the periphery to correspond to the said notches in the feed wheel.
14. In an air gun, a stock, a barrel and 110 operative mechanism supported by the said stock, the said stock having cavities for housing parts of the said mechanism, the said stock being composed of two mating members, each of which has recesses that 115 co-operate with the recesses of the other to complete the said cavities, means for holding the parts of the gun together in the form of a metal band that encircles the said parts
- 120 125

of the gun, and a portion of the said band being extended above the barrel and formed so as to be adapted to serve as a sight.

15. In an air gun having a bullet chamber at the rear end of the barrel, the side wall of the said chamber having a perforation for providing a housing for a spring plunger that serves to retain the bullet in the said chamber, a closure for the outer end

of the said housing, and the said closure being in the form of a metal band that encircles the adjacent parts of the gun structure.

16. In an air gun as described in claim 15, the said band being extended above the said gun structure and formed so as to be adapted to serve as a sight.

FREDERICK HUMBERT FAIRWEATHER.
